UNITED STATES PATENT OFFICE.

SAMUEL BERGSTEIN, OF MIDDLETOWN, OHIO, ASSIGNOR TO THE INTERSTATE FOLDING BOX COMPANY, OF MIDDLETOWN, OHIO.

PAPER FOLDING BOX AND THE LIKE.

Application filed July 17, 1922. Serial No. 575,451.

This invention relates to improvements in paper folding boxes,—having particular reference to paper folding boxes, or cartons, adapted when open to display their contents or a sample of their contents,—the type of box being especially adaptable for display goods, as toilet articles, chewing gum, etc., on counters and shelves of retail stores.

An object of the invention is to provide a folding box of this character of simple construction,—the entire box being made of one piece of paper stock—which will have a foldable flap formed in the bottom thereof, adapted when adjusted to act as a support to hold the box raised at an angle so that the contents of the box will be displayed to better advantage.

A further object of the invention is to provide foldable margins along the upper side edges and along a portion of the lid of the box which serve to improve the appearance of the box when open, and also to reinforce the construction and to hold the lid in open position.

A further object of the invention is to provide a novel arrangement for carrying an advertisement on the outside of the lid which will be brought to the desired position relative to the contents of the box, to present the advertisement effectively when the box is opened and arranged as a display device.

Other features of the invention relate to details of construction, which tend to improve and cheapen the product, and which will be described in the detailed specification.

In the accompanying drawings, the improved box is illustrated in a number of modified forms of preferred construction,—the characteristics of the invention being expressed in each form.

In the drawings:

Fig. 1 is a diagrammatic view illustrating the one-piece paper blank from which the box is made in one form, and the manner of cutting the stock to minimize waste of material;

Fig. 2 is a side elevation of a folding box made of a blank illustrated in Fig. 1,—the lid of the box being open, and the flap arranged to support the box at an angle;

Fig. 3 is a sectional view of the box illustrated in Fig. 2 taken on lines 3—3, the

lid of the box and the supporting flap being in closed relation;

Fig. 4 is a view illustrating the box in knocked-down form as arranged for handling and shipping in bulk;

Fig. 5 is a perspective view of the box set up for displaying its contents.

As here shown, the box illustrated in Figs. 1 to 4 is made of a single piece of paper which is scored to form the folding lines of the form, the folding lines acting to divide the form into parts —1, —2, —3, —4, which are adapted to be folded relative to each other to form the rectangular-shaped body of the box,—part —4 having a marginal extension —5 which is adapted to overlap and to be pasted to the coacting edge of part —1 to hold the parts together.

The lid of the box is formed of parts —6 and —7 scored on medial lines —8 to provide for folding one part of the lid relative to the other,—part —7 having a flap —9 foldable on line —10 and adapted to overlap the edge of the box, as illustrated in Fig. 3, when the lid is closed. Webs or flanges —11, foldable inwardly in a compound fold on lines —12, —13 and —14 when the box is closed, are interposed between parts —2 and —4 respectively, and part —6 of the lid to strengthen the construction, to hold the lid in raised position and to improve the appearance of the box when used as a display device. Part —6 of the lid has a part —15 of ornamental design cut out thereof,—the part being in effect an upward extension of part —7 when part —7 is folded inwardly over part —6 as best illustrated in Fig. 2, and serving to provide space for part of an advertisement displayed on the lid. The advertisement is printed on the outer surface of parts —7 and —15 and will face inwardly when the lid is folded as shown in Fig. 2.

The bottom of the box consists of foldable parts slotted on lines —19 and —20 and scored on lines —21, 22, and 23, and folded in relation one to the other, as illustrated in Fig. 3,—parts —16 and —18 being folded longitudinally and part —17 transversely of the box to form the bottom thereof,—part —17 having a marginal flap —24 foldable on line —25 and adapted to overlap the lower edge of the box and to be pasted down to bind the parts together. Part —18 has a flap —26

partially cut out thereof, and adapted to be bent outwardly on line —27 and to be shaped into a support, as illustrated in Fig. 2, to hold one end of the box in raised position to better present the contents of the box to view,—the edge —28 of the flap being adapted to be tucked into a retaining flap —29 formed in part —17 to hold flap —26 in its adjusted position. As shown in Fig. 3 the flap —26 and webs —11 are folded flat within the outer lines of the box when the parts are in closed relation. In the relation of the box illustrated in Fig. 2 bottom portion 18 is intermediate portions 16—17, thus the aperture in part 18 caused by severing part 26—28 therefrom is covered on opposite sides to form a closed bottom of the box.

The knocked-down form of the box illustrated in Fig. 4 represents merely common practice in preparing paper folding boxes for handling and shipping in bulk.

The feature of novelty of the general arrangement of parts —6 —7 and 15 consists in the adaptability of the parts together with the coacting part of the lid to have an advertisement printed on the outside thereof, and to properly display the advertisement on

the box either as closed or open. This permits of printing all desired subject matter on the box in one operation and tends, therefore, to cheapen the product.

Having described my invention, I claim:

A paper folding box formed of a one-piece blank comprising top and bottom portions arranged in a straight line one with another, side and end portions contiguous in a straight line one with another extended at right angles to and intermediate said top and bottom portions, other bottom portions arranged at right angles to said side and end portions, extended laterally therefrom parallel with said first named bottom portion, said bottom portions being adapted to be folded in superposed relation one part to another to form the bottom of the box, an intermediate bottom portion having a part severed therefrom, remaining attached to an end portion, adapted to be extended downward and shaped into a pedestal and interlocked with the lowermost bottom portion to support the box at an angle to display the contents thereof.

In testimony whereof, I affix my signature.

SAMUEL BERGSTEIN.
